SKI PANTS

Paul Haberfeld, Portland, Oreg., assignor to Jantzen Knitting Mills, a corporation of Oregon

Application October 11, 1946, Serial No. 702,801

2 Claims. (Cl. 2—232)

1

This invention relates to garments and more specifically to ski pants, the legs of which are adapted to extend within the shoes of the wearer.

For many purposes it is desirable that the legs of garments be so designed as to be adapted to be tucked or placed within the shoes of the wearer. This is true, for example, when the garments are to be worn in skiing and it is desired to provide a garment which fits snugly, which is warm, and which allows the wearer maximum freedom of motion but at the same time prevents penetration of snow or moisture. When the legs are so placed, there is present, in the absence of means for anchoring them securely to the foot, the obvious tendency to creep up the leg of the wearer, and ultimately become free of the shoe. To avoid this difficulty it is common practice to secure the leg to the foot by means of a band or strap affixed to the leg of the garment transversely across the bottom thereof and adapted to lie under the arch of the wearer. Such an arrangement, however, is unsatisfactory in that it permits the rear portion of the trouser cuff to creep out of the shoe, and also permits a certain amount of twisting of the leg so that it becomes displaced on the person of the wearer. Existing garments have the further disadvantage that they do not cover the forepart of the wearer's foot, which may as a consequence become chafed and sore from contact with the unyielding surfaces of boots or shoes.

It is an object of the present invention to provide a garment the legs of which are adapted to lie within the shoes of the wearer and to be firmly anchored therein so that no portion of the cuff is free to become retracted from said shoes.

It is another object to provide a garment the legs of which are firmly anchored in such a manner as to overcome any tendency toward rotating or twisting on the legs of the wearer when in use.

It is still another object to provide a garment which will fit snugly and provide a maximum of warmth.

It is a further object to provide a garment which, when used in skiing, or other winter sports, will prevent access of snow inside the shoes of the wearer.

It is still a further object to provide a garment which adequately will protect the forepart of the wearer's foot, both by supplying added warmth and by furnishing a layer of heavy material between foot and boot which tends to prevent rubbing, chafing, or bruising.

The foregoing and other objects of the present invention are accomplished by means of a gar-

2

ment the construction of which is clearly disclosed in the following description, and the novel features of which are particularly pointed out in the appended claims, reference being had to the accompanying drawings wherein:

Fig. 1 is a side view of the lower portion of a pants leg tucked within the top of a boot in the manner in which ski pants customarily are worn.

Fig. 2 is a detail side view of the lower portion 10 of a pants leg positioned on the foot of the wearer and illustrating the novel features of the invention.

Fig. 3 is a detail rear view of the lower portion of the pants leg of Fig. 2 taken along the line 3—3.

Fig. 4 is a detail bottom view of the pants leg of Fig. 3, taken along the line 4—4.

As is well known, ski pants are usually so tailored that the legs thereof will fit relatively loosely about the legs of the wearer. The length of the legs of the pants usually is such that the lower ends thereof terminate in a substantially horizontal plane above the heels of the wearer yet somewhat below the ankles. The lower ends of the legs of the pants, therefore, may be extended downwardly a considerable distance into the ski boots.

As illustrated in the drawings, the leg 10 of the ski pants of the invention is provided with a heelpiece 11, a transverse stirrup strap 12, and a front flap or apron 13. The heelpiece 11 comprises a strip of material affixed to the lower rear portion or cuff of the leg and extending longitudinally therefrom, the other end being affixed to the strap 12, preferably at its lower extremity. The heelpiece may be tailored in diverse forms, but preferably is sufficiently wide to cover a major portion of the heel area. It is further desirable that it be relatively narrow at the point of attachment to the cuff in order to minimize the likelihood of a fold being formed in the seam between the cuff and heelpiece. Such a fold obviously would be bulky and cause discomfort to the wearer. The heelpiece may be fabricated from any desired material, elastic or otherwise.

The transverse strap 12, connects the sides of the cuff and is adapted to lie under the arch. It serves the dual function of helping to anchor the pants leg in place inside the shoe of the wearer and also of furnishing a place of attachment of the lower end of the heelpiece 11. It preferably is made from elastic material so as to afford some degree of freedom of motion but at the same time insuring against retraction of the cuff from the top of the boot.

The flap or apron 13 preferably is a roughly

triangular piece of material affixed to the forepart of the cuff and adapted to cover the forepart of the wearer's foot. To afford the maximum degree of warmth and protection, it preferably extends transversely to both terminals of the transverse strap 12 and longitudinally a sufficient distance to extend approximately to the toes of the wearer.

The construction of the novel garment of the invention is thus such as to afford means for firmly anchoring a pants leg inside a boot, as a ski boot. It prevents rotation of the leg on the leg of the wearer and prevents the creeping up of any portion of the cuff, particularly the rear portion, so as to be withdrawn from the top of the boot. By means of the forwardly-located protective element there is furnished means for protecting the forward part of the foot from chafing or rubbing while at the same time furnishing a desirable degree of warmth. The ensemble provides a snugly fitting garment which permits an adequate and desirable degree of freedom of motion, yet effectively inhibits access of snow to the interior of the boot.

Although the invention has been described with particular reference to ski pants, it will be apparent that it is applicable also in the construction of other types of garments.

Having thus described my invention, what I claim as new and desire to protect by Letters Patent is:

1. A pair of trousers of the class described, the legs thereof being adapted to fit relatively loosely about the legs of the wearer, the lower ends of said legs terminating in a substantially horizontal plane between the ankle and the heel of the wearer, the leg ends being adapted to be placed within the shoes of the wearer, a stirrup strap extending transversely across the bottom of each of said legs and adapted to lie under the arch of

the foot of the wearer, a heelpiece extending longitudinally from the rear edge of each of said legs and attached to said strap substantially at its lowermost extremity, said heelpiece being adapted to hold in place within the shoe said rear edge of each of said legs, and an apron extending longitudinally from the front edge of each of said legs and reaching laterally substantially to the terminal portions of said strap, said apron being adapted to cover and protect the forepart of the foot of the wearer.

2. A pair of trousers of the class described, the legs thereof being adapted to fit relatively loosely about the legs of the wearer, the lower ends of said legs terminating in a substantially horizontal plane between the ankle and the heel of the wearer, the leg ends being adapted to be placed within the shoes of the wearer, a stirrup strap secured at its opposite ends to the opposite side edges of the lower end of each of said legs, a heel piece secured to the rear edge at the lower end of each of said legs and extending downwardly therefrom and around the ball of the heel of the wearer and forwardly therefrom, the forward end of said heel piece being secured to the midpoint of said strap.

PAUL HABERFELD.
